TOY MUSICAL INSTRUMENT OR SIMILAR ARTICLE

Max Feintuch, Brooklyn, N. Y.

Application January 4, 1954, Serial No. 28,339

Term of patent 3½ years

(Cl. D34—15)

To all whom it may concern:

Be it known that I, Max Feintuch, a citizen of the United States, residing at Brooklyn, in the county of Kings and State of New York, have invented a new, original, and ornamental Design for a Toy Musical Instrument or Similar Article, of which the following is a specification, reference being had to the accompanying drawing, forming part thereof.

I claim:
The ornamental design for a toy musical instrument or similar article, as shown.
